UNITED STATES PATENT OFFICE

WILLIAM M. DOLKE, OF STEVENS POINT, WISCONSIN

BELT BUCKLE

Application filed April 16, 1929. Serial No. 355,519.

This invention relates to new and useful improvements in buckles.

One of the objects of my invention is the provision of a buckle adapted to be used in connection with belts of various characters and resides in the construction of a buckle which can be quickly and easily detached from one end of the belt while means is provided for engaging the other end of the belt with the buckle for holding the belt in active position.

Another object of the invention is the provision of a buckle adapted to be used in connection with belts and is so connected to the belt as to provide for a considerable saving of leather in the manufacture of belts and at the same time is extremely efficient in cooperating with the ends of the belt for retaining the same in its proper position.

A further object of the invention is the provision of a belt buckle wherein the parts thereof are extremely simple and so arranged as to be compact in form when in operative position whereby they will present a neat, attractive and smooth fitting appearance so that there will be no uneven parts which will have a tendency to press toward or against the body of the wearer.

A still further object of the invention is the provision of a belt buckle wherein the normally free end of the belt can be quickly and readily engaged with the buckle or removed therefrom and which, during the active use of the belt will have a tendency to tightly grip the normally free end when any stress or strain is applied to the belt so that it will be practically impossible to disconnect the normally free end from the buckle while the belt is in use.

A still further object of the invention is the provision of a belt buckle wherein the metal parts of the buckle are inter-connected and the clamping member is adjustably mounted with respect to the body of the buckle and the parts are so arranged that one end of the belt may be quickly and readily attached to or detached from the buckle, and the other end after encircling the wearer can be quickly and easily engaged with the buckle and be tightly secured against movement.

The parts also being arranged so that any strain applied to the belt will have a tendency to tighten the normally free end in such a manner as to quickly distribute the pulling strain throughout the body of the buckle.

With the above and other objects in view, the invention consists in the novel features of construction, the combination and arrangement of parts hereinafter more fully set forth, pointed out in the claims and shown in the accompanying drawings wherein:

Figure 1 is an elevation looking toward the inside of the buckle with the belt ends in position;

Figure 2 is a view similar to Figure 1, with one of the belt ends removed;

Figure 3 is a transverse sectional view on the line 3—3 of Figure 1;

Figure 4 is a longitudinal section on the line 4—4 of Figure 1;

Figure 5 is an enlarged longitudinal section of the buckle with the belt ends removed; and,

Figure 6 is a detail perspective view of the clamping plate.

Referring more particularly to the drawings, it will be noted that the body of the buckle comprises a curved front or face part 1. Ordinarily, prior to the shaping of the buckle, the body comprises a loop and in order to properly form the buckle, the back 2 of the loop is pressed inwardly toward the front 1; this operation of folding the side walls upon themselves, is shown at 3, to form a channel 4.

In depressing the back portion of the loop inwardly toward the front part 1, one end of the back is pressed inwardly a distance slightly beyond the other end, thus forming a substantially tapering channel between the front and back parts. The walls of the depressed part from the overturned part 3 to the back part 2 being curved or tapered toward one end of the body as will be clearly illustrated in Figure 5, thus forming a tapering channel through the body.

The back part 2 is formed with a longitudinal slot 5 which receives the headed pin 6 carried by the curved clamping plate 7. This clamping plate normally moves within the

tapered channel between the front and back part and is restricted in its movement by the pin 6 operating in the slot 5.

The back part 2 carries the headed studs 8 which are adapted to be engaged by the sockets 9 carried by one end of the belt 10. The end of the belt 10 which carries the sockets 9 is preferably that end which is secured to the buckle and is retained in this position at all times during the use of the belt whether the normally free end of the belt is engaged with the buckle or not. In order to retain the attached end of the belt against lateral movement with respect to the body of the buckle, opposed tabs or fingers 11 are cut out of the back portion and extended transversely of the buckle, as shown in Figures 1 and 2. These tabs or fingers are disposed outwardly of the belt 10 and will prevent the belt from moving laterally away from the buckle, but the belt can be readily engaged with the buckle and be disposed beneath the fingers 11 by pressing inwardly upon the edges of the belt so that they will engage beneath these fingers prior to the fastening of the sockets 9 onto the headed studs 8.

As shown in Figure 5, the parts of the buckle are arranged in operative position. In using the device, the end of the belt carrying the sockets 9 may be readily engaged with the studs 8 so that the belt can be quickly arranged for use. When it is desired to engage the normally free end with the buckle, the rounded or tapering end of the belt is inserted into the buckle behind the front 1 thereof, from the right of the illustration in Figure 5, the leather part of the belt engaging the clamping plate 7 and moving the same to the left. After the belt has been drawn through the buckle to a point beyond its required position, the end is then released and as the belt loosens, moving toward its required position, it will cooperate with the roughened or knurled surface of the clamping plate, moving the clamping plate into the tapering channel, and it will be noted that due to the tapering of this channel, the belt will be tightly wedged between the front face 1 of the buckle and the clamping plate.

It will be noted that the side walls 12 of the clamping plate are rounded toward each end and these rounded side walls operate in the channel 4 formed by the overturned side walls of the body of the buckle and as the inner wall of the channel 4 is tapered due to the relative position of the back 2, the clamping plate will have a tendency to cooperate with the inner edge of this wall and be quickly clamped in position during the movement of the clamping plate in the channel between the front and back parts of the buckle.

From this, it will be apparent that any additional strain applied to the belt will have a tendency to tightly wedge the plate 7 against the belt and limit its movement in one

direction. However, when it is desired to release the normally free end of the belt, it is given a pull in the opposite direction in order to release the plate 7 and as soon as the plate 7 is released, it can be held in this position by the fingers until the normally free end of the belt is withdrawn from the buckle.

In attaching the sockets 9 to the end of the belt which is to be secured to the buckle, I prefer to position these sockets at a slight distance from the end of the plate and round off the end of the belt, as shown in Figure 1. This end of the belt which projects beyond the sockets will have a tendency to guard the wearing apparel against contact with the sharp edges of the buckle, and will also provide means whereby the end of the belt may be grasped by the fingers for disconnecting the sockets 9 from the studs 8. In contracting the body of the buckle, it is preferred to stamp out the body in one piece and then quickly fold the same so that the edges thereof are brought together on a center line at the back of the buckle, as shown at 13, and each side of the center of the back portion 2 is recessed to form the slot 5.

Attention is directed to the fact that in the use of a buckle of this character, a considerable saving is carried out in the application of the belt to the buckle, as the sockets 9 can be positioned very close to the end of the strip of leather which goes to form the belt, thus eliminating the extra amount of leather which is generally used to be wrapped around a cross bar of a portion of the buckle in the manufacture of belts at the present time. Furthermore, the buckle itself is comparatively free of obstructions so that when the normally free end of the belt is in position, the buckle as well as the overlapped ends of the belt will rest snugly against the body of the wearer and there will be no unusual projections to be pressed against the body during use.

It will be noted that the ends of the side walls 12 of the clamping plate are rounded off so that regardless of which end of the plate 7 is inserted into the body of the buckle, the clamping action of the plate will be the same.

I claim:

1. In a belt buckle, a channelled body including a front and back wall with one end of the back wall positioned nearer the front wall than the other end, said back wall having its ends terminating at a point inwardly of the ends of the front wall and provided with a central longitudinal slot, and a clamping plate movable within the channelled body and having a headed pin engaged with said slot.

2. In a belt buckle, a channelled body including a front and back wall with the ends of the back wall terminating short of the ends of the front wall, said back wall having

a central longitudinal slot and a clamping plate movable within the channelled body and having a headed pin engaged within said slot.

5 3. A belt buckle including front and back walls with the back wall offset relative to the side portions to form channels, said back wall being shorter than the front wall and having a longitudinal slot, a clamping plate
10 movable between the front and back walls and having side flanges movable in the channels, and a headed pin carried by said clamping plate cooperating with the slot for limiting the movement of the clamping plate relative to the back plate.

15 In testimony that I claim the foregoing I have hereunto set my hand at Milwaukee, in the county of Milwaukee and State of Wisconsin.
